UNITED STATES PATENT OFFICE.

FRANK LE ROY, OF ABERDEEN, WASHINGTON.

PROPELLING MEANS FOR BOATS.

Application filed January 28, 1925. Serial No. 5,345.

To all whom it may concern:

Be it known that I, FRANK LE ROY, a citizen of the United States, residing at Aberdeen, in the county of Grays Harbor 5 and State of Washington, have invented new and useful Improvements in Propelling Means for Boats, of which the following is a specification.

This invention contemplates the provision 10 of a simple, novel and durable construction of means for propelling boats, wherein use is made of one or more endless chains mounted to move longitudinally of the boat and provided with a series of paddles, the 15 paddles carried by the lower run of the chain being submersed for propelling the boat.

The nature and advantages of the invention will be better understood when the following 20 detailed description is read in connection with the accompanying drawings, the invention residing in the construction, combination and arrangement of parts as claimed.

25 In the drawings forming part of this application, like numerals of reference indicate similar parts in the several views, and wherein:

Figure 1 is a side elevation.

30 Figure 2 is a sectional view taken on line 2-2 of Figure 1.

Figure 3 is a sectional view taken on line 3-3 of Figure 2.

35 Figure 4 is a bottom plan view of the boat.

Referring to the drawings in detail, 10 represents a boat of any well known construction, the bottom of which at either side of the longitudinal center is provided with 40 longitudinal openings to accommodate the propelling mechanism to be presently described.

The mechanism embodies spaced parallel shafts which are arranged transversely of 45 the bottom as shown in Figures 2 and 3, these shafts being indicated at 11 and 12 respectively. Each shaft supports a pair of drums or the like 13 which are arranged to operate in the openings in the bottom of the 50 boat above referred to. These drums are of course used in pairs, and trained over each pair of said drums is an endless belt 14 which is provided with a series of paddles

15. Consequently there is one of these endless belts arranged longitudinally at each 55 side of the longitudinal center of the boat, operating in the openings above referred to, and disposed so that the paddles 15 on the lower run of each belt are submersed in the water to effectively and advantageously 60 propel the boat, while the paddles carried by the upper run of the belt are always arranged above the water level. The belts may be operated in any suitable manner, but I preferably provide the shaft 11 with a 65 crank portion 16 which is associated with a pitman or connecting rod 17 which is adapted to be reciprocated by a motor not shown. Upon inspection of Figure 2 it will be noted that each endless chain operates in a suitable 70 guide 18, each guide being of substantially inverted U-shaped formation in cross section, and of a length equal to the length of the opening above referred to, there being one of these guides arranged in 75 each opening as shown. The guides are also used to prevent water from finding its way into the boat, each guide having its outer side 19 comparatively wide to extend beneath the bottom of the boat, and terminating substantially in a plane with the lower edges of the paddles 15.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

The combination with a boat having spaced longitudinal openings in the bottom thereof, an inverted channel member of U-shaped formation in cross section arranged within the boat and covering the adjacent opening, to prevent water from entering in the boat through said opening, the corresponding inner walls of the respective members reposing upon the adjacent edges of said opening, the corresponding outer walls of said members projecting through said opening, flanges projecting laterally from the last mentioned walls but reposing upon 100 the sides of the boat to assist in holding 105

said members in position, spaced parallel to transverse shafts journaled on the walls of said channel members, spaced drums carried by said shafts and arranged in each 5 channel member, an endless belt trained over each pair of drums, paddles carried by said belt and adapted to pass through

the water with the lower run thereof, a crank portion formed on one of said shafts, and a reciprocating rod connected with said 10 crank portion for rotating said shaft for the purpose specified.

In testimony whereof I affix my signature.

FRANK LE ROY.
